UNITED STATES PATENT OFFICE.

CLAYTON H. SHARP, OF WHITE PLAINS, NEW YORK.

DESIGN FOR A REFLECTOR.

40,644.

Specification for Design. Patented Apr. 19, 1910.

Application filed February 23, 1910. Serial No. 545,548. Term of patent 7 years.

To all whom it may concern:

Be it known that I, CLAYTON H. SHARP, a citizen of the United States, residing at White Plains, in the county of Westchester and State of New York, have invented a certain new, original, and ornamental Design for Reflectors, of which the following is a specification, reference being had to the accompanying drawing, forming part hereof.

The figure is a perspective view of a reflector, showing my new design.

I claim:

The ornamental design for a reflector, as shown.

CLAYTON H. SHARP.
